Primary Examiner—Paula A. Mortimer
Attorney, Agent, or Firm—Paul M. Denk**[57]****CLAIM**

The ornamental design for the articulated interlinked segmented belt, as shown and described.

DESCRIPTION

FIG. 1 is an isometric view of an articulated interlinked segmented belt showing my new design, the broken line showing of the human form is for illustrative purposes only and forms no part of the claimed design;

FIG. 2 is a front elevational view thereof;

FIG. 3 is an end elevational view thereof, the opposite end is a mirror image;

FIG. 4 is a rear elevational view thereof;

FIG. 5 is a top plan view thereof;

FIG. 6 is a bottom plan view thereof;

FIG. 7 is a top plan view of a link of the articulated interlinked segmented belt shown separately for purposes of illustration;

FIG. 8 is a left end elevational view thereof;

FIG. 9 is a front elevational view thereof; and,

FIG. 10 is a right end elevational view thereof.
